UNITED STATES PATENT OFFICE.

GOTTLOB BINDER, OF ROCHESTER, NEW YORK, ASSIGNOR TO AMERICAN LAUNDRY MACHINERY COMPANY, OF CINCINNATI, OHIO, A CORPORATION OF OHIO.

REVERSING MECHANISM.

1,160,687.

Specification of Letters Patent. Patented Nov. 16, 1915.

Application filed June 19, 1913. Serial No. 774,581.

To all whom it may concern:

Be it known that I, GOTTLB BINDER, of Rochester, in the county of Monroe and State of New York, have invented certain new and useful Improvements in Reversing Mechanisms; and I do hereby declare the following to be a full, clear, and exact description of the same, reference being had to the accompanying drawings, forming a part 10 of this specification, and to the reference-numerals marked thereon.

My present invention relates to reversing mechanisms adapted for employment with various types of machinery, where it is desirable to move an element alternately in opposite directions, such, for instance, as washing machines used for laundry purposes, in which the washing cylinder is rotated first in one direction and then in the other for a predetermined number of revolutions, and it has for its object to provide an improved construction and arrangement by which the parts, where friction is set up, may run in a bath of oil and an easier and more regular movement is obtained for the elements whose direction of movement is reversed at predetermined intervals.

To these and other ends the invention consists in certain improvements and combinations of parts, all as will be hereinafter more fully described, the novel features being pointed out in the claims at the end of the specification.

In the drawings: Figure 1 is a view in side elevation of a preferred embodiment of my invention, showing its application to a washing machine, a portion of which is broken away; Fig. 2 is a sectional view on the line 2^a—2^a of Fig. 3; Fig. 3 is a sectional view 35 on the line 3^a—3^a of Fig. 2; Fig. 4 is a sectional view on the line 4^a—4^a of Fig. 3, and Fig. 5 is a detail elevation showing the member for manually controlling the belt shifter disengaged from the reversing gear.

Similar reference numerals throughout the several figures indicate the same parts.

In the present embodiment of the invention, 1 designates the body of a washing machine of usual type, embodying a rotating cylinder whose movement is reversed at predetermined intervals, and 2 is a gear wheel which is connected in any suitable manner

with the cylinder of the washing machine, although it will be understood that for the purposes of my invention, the gear wheel 2 55 might be an element of any mechanism which it is necessary to move alternately in opposite directions. The gear wheel 2 is actuated by a shaft 3 having a pinion 4 in engagement therewith. The shaft 3 is 60 mounted in the bearing 5 of the support or bracket 6, which is fixedly attached to the body 1 and constitutes the driven member of the present embodiment. Said shaft also carries a fixed pulley 7 and loose pulleys 8. 65

9 designates oppositely driven belts which are adapted to be shifted so as to drive the fixed pulley 7 in one direction or the other or to permit the shaft 3 to remain idle, as shown in Fig. 1, and my present invention 70 has to do more particularly with the means for shifting said belts alternately in opposite directions to secure this reversal of movement.

10 is the belt shifter provided with arms 75 11 which engage the respective belts, and which is slidably arranged on the guide post 12, the latter being suitably mounted upon the bracket 13, to be described more fully hereinafter. The shifter 10 carries the arm 80 14, which forms a bearing for the rotatable rod 15, the latter being attached to said arm 14, as shown in Figs. 1 and 4, and being journaled in the stationary bearing 16, within which it has a sliding as well as a rotating 85 movement. The shifter 10 is adapted to be manually operated by means of said rod 15, and to this end the latter is provided with a weighted handle portion 17 to enable it to be turned. The rod 15 has fixed thereon a 90 member 18 which is provided with a pair of cam surfaces 19, and also has a notch or recess 20 for a purpose that will presently be made clear. The cam surfaces 19 are arranged for engagement with a pair of stationary projections 21, whereby when the rod 15 is rotated, said projections will cause a longitudinal movement thereof sufficiently to bring both belts into engagement with the loose pulleys on the shaft 3. When the member 18 is in its normal position, as shown in Fig. 4, it is engaged by an actuator 22 having a pin 23 co-operating with the aforementioned recess 20 and through the movement

of said actuator, which I am now about to describe, the member 18, together with the rod 15 is given a back and forth movement, causing first one pulley and then the other 5 to engage the fixed pulley 7.

In order to effect the necessary oscillation of the actuator 22, I provide a driving member, preferably in the form of a worm 24 which is fixed upon the hub of the outer 10 loose pulley 8, as shown in Fig. 4. Continuous movement of the worm is obtained by making the corresponding belt 9 sufficiently wide to engage partially at all times with its loose pulley. The worm 24 engages with 15 the worm gear 25, loosely disposed on the bearing 26, the latter being adjustably secured in the casing 27, which completely incloses the bottom portion of the reversing gearing and is preferably integral with the 20 bracket 13, said bracket being held in position by means of the cup 28, which is secured within the aforesaid bearing 5 and receives the outer end of the shaft 3.

29 designates a cam formed on the sleeve 25 30 which is provided with suitable projections engaging corresponding recesses in the worm gear 25 whereby the cam is driven constantly with the worm gear. Said cam is operatively associated with the actuator 22 30 which is pivotally mounted at 31, and in order to obtain properly equalized movement of the belt shifter in both directions, it is desirable to provide a compensating means between the cam and the actuator. To this 35 end, I prefer not to connect the parts directly, but to afford an indirect connection whereby I may effect movement of the actuator 22 at substantially constant speed at every point of its movement. To this end, 40 I provide a lever 32 which is pivotally mounted at 33, and has a bifurcated end portion comprising parallel arms 34, between which are arranged the roller bearings 35, disposed for engagement with the 45 cam 29. It will be seen that by reason of the relative positions of the cam 29 and the pivotal point 33, the movement of the end of the lever 32, or of the roller bearings, is very nearly in a straight horizontal line, its 50 movement being at substantially a constant rate of speed for all positions. The movement of the lever 32 is communicated to the actuator 22 by connecting said parts in a suitable manner, and for this purpose the actuator 55 is preferably provided with a bifurcated tail piece 36 having projections 38 engaging in recesses 37 formed on the arms 34 of the lever 32.

39 is a lubricating wick secured in a suitable recess on the actuator 22, and arranged

to engage the edge of the cam 29, so as to supply the latter constantly with oil.

I claim as my invention:

1. In a reversing mechanism, the combination with a rotary member, of fast and 65 loose pulleys mounted thereon, belts coöperating with the pulleys, a shifter for controlling the position of the belts, a pivotally mounted actuator connected to the shifter, a pivotally mounted lever having connection 70 with the actuator, and a cam in coöperative engagement with said lever.

2. In a reversing mechanism, the combination with a rotary member, of fast and 75 loose pulleys mounted thereon, belts coöperating with the pulleys, a shifter for controlling the position of the belts, a pivotally mounted actuator connected to the shifter, a cam for moving the actuator, and an intermediate connecting device between the cam 80 and the actuator, said device being pivoted independently of the actuator and having operative connection therewith, the cam having engagement with the connecting device.

3. In a reversing mechanism, the combination with a rotary member, of fast and 85 loose pulleys mounted thereon, belts coöperating with said pulleys, a shifter for controlling the position of the belts, a pivoted actuator connected to the shifter, a lever 90 pivotally mounted independently of the actuator and having connection therewith, and a rotary cam arranged to engage and control the movements of said lever.

4. In a reversing mechanism, the combination with a rotary member, of fast and 95 loose pulleys mounted thereon, belts coöperating with the pulleys, a shifter for controlling the position of the belts, a pivotally mounted actuator connected to the shifter, a 100 lever mounted independently of the actuator and having connection therewith, said lever being provided with a bifurcated end portion formed of parallel arms, antifriction rollers arranged between said arms, and a 105 rotary cam positioned between the rollers.

5. In a reversing mechanism, the combination with a rotary member, of fast and 110 loose pulleys mounted thereon, belts coöperating with the pulleys, a shifter for controlling the position of the belts, a movably mounted actuator connected to the shifter, a movably mounted lever having connection with the actuator, and operating means arranged to engage said lever.

GOTTLOB BINDER.
